US0D1005244S

(12) **United States Design Patent** (10) **Patent No.:** **US D1,005,244 S**
(45) **Date of Patent:** ** *Nov. 21, 2023

(54) **REMOTE CONTROL**

(71) Applicant: **Lutron Technology Company LLC**,
Coopersburg, PA (US)

(72) Inventors: **Gregory Altonen**, Easton, PA (US);
Chris Dimberg, Easton, PA (US);
Jason C. Killo, Emmaus, PA (US);
Matthew Philip McDonald,
Phoenixville, PA (US); **Daniel L.**
Twaddell, Allentown, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/848,518**

(22) Filed: **Aug. 3, 2022**

(57) **CLAIM**

The ornamental design for a remote control, as shown and
described.

DESCRIPTION

FIG. 1 is a front perspective view of a remote control
showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view of a second embodiment
thereof;

FIG. 8 is a front view thereof;

FIG. 9 is a left side view thereof;

FIG. 10 is a right side view thereof;

FIG. 11 is a top view thereof; and,

FIG. 12 is a bottom view thereof.

1 Claim, 8 Drawing Sheets

Related U.S. Application Data

a continuation of application No. 29/640,715, filed on Mar. 16, 2018, now Pat. No. Des. 913,254.

(58) Field of Classification Search

CPC 39/086; H05B 39/088; G08C 17/02; H03K 17/962
